ATTORNEYS

UNITED STATES PATENT OFFICE.

JOHN A. KAYE, OF SAULT STE. MARIE, ONTARIO, CANADA.

RETURN ENVELOPE.

Application filed May 17, 1924. Serial No. 713,894.

To all whom it may concern:

Be it known that I, JOHN A. KAYE, a subject of the King of Great Britain, residing at Sault Ste. Marie, in the Province of 5 Ontario and Dominion of Canada, have invented certain new and useful Improvements in Return Envelopes, of which the following is a specification.

The present invention relates to an envelope and has for its object to provide a device of this character which embodies novel features of construction, whereby after it has once been sealed and opened it can be effectively sealed a second time.

15 Further objects of the invention are to provide an envelope of this character which can be inexpensively formed from a single blank of paper or like material, which can be handled in the same manner as an ordinary envelope, and after being originally mailed can be used by the recipient thereof for sending back his reply.

The invention further contemplates a re-mailable envelope in which the address will 25 be at all times clearly displayed, so that there will be no possibility of confusion or mis-carriage, and which can be effectively sealed so that it will be impossible to obtain access to the contents thereof without opening or 30 mutilating the same.

While a preferred embodiment of the invention is shown and described in detail for illustrative purposes, it will be understood that many modifications and changes 35 can be made in the details of construction without departing from the spirit of the invention.

For a full understanding of the invention reference is to be had to the following description and accompanying drawings, in 40 which—

Figure 1 is a top plan view of the paper blank from which the envelope is adapted to be formed.

45 Figure 2 is a plan view of the reverse side of the blank.

Figure 3 is a view of the back of the envelope when it is ready to be sealed for the first time, the original sealing flap being 50 shown in an open position and the extension of the bottom flap being shown in a folded position.

Figure 4 is a front view of the envelope after it has been initially sealed and is ready 55 for mailing the first time.

Figure 5 is a rear view thereof.

Figure 6 is a rear view of the envelope after it has been opened the extension being unfolded and in position preparatory to sealing the envelope a second time. 60

Figure 7 is a front view of the envelope in the condition shown by Figure 6.

Figure 8 is a front view of the envelope after it has been sealed a second time.

Figure 9 is a rear view thereof. 65

Referring to the drawing, which illustrates one of many possible embodiments of the invention, the numeral 1 designates the front of the envelope and has the size and shape of the envelope which it is desired 70 to use. End flaps 2 project from the ends of the front 1, and are adapted to be folded back against the same on the fold lines 2^a. The bottom flap 3 projects from the bottom of the front 1 and is also adapted to be 75 folded against the back thereof on the fold line 3^a.

The bottom flap 3 has a tapered formation and terminates in an extension 4, which is of a sufficient size to cover the front of 80 the envelope. The base 4^a of the extension fits against the upper portion of the back of the envelope, and the end flaps 2 are shown as provided with adhesive 5 which is applied thereto in such a manner that it can 85 be utilized for sticking the end flaps to the bottom flap 3 and base 4^a of the extension 4.

The front 1 of the envelope is provided with a return card 6 which includes the 90 name and address of the sender and is shown as applied to the front of the envelope in the usual position at the upper left-hand corner thereof. A stamp 7 may be placed upon the envelope in the usual position at the upper right-hand corner thereof. 95 A place is provided for the address which may be written directly upon the envelope if such is desired, although in the present instance the envelope is formed with a window 8, so that an address which is applied to an enclosure will be visible through the window and can be utilized as the address for the envelope. 100

The top flap 9 is adapted to be folded 105 against the back of the envelope on the fold line 9^a, and is provided with adhesive 10, so that the envelope can be sealed in the usual manner. The top flap is sufficiently large so that it will form a pocket to receive 110 the folded extension 4. This extension may be folded in any suitable manner, although

for the purpose of convenience it is shown as first folded upon the longitudinal fold lines 4^b, after which the ends are turned back on the transverse fold lines 4^c. The 5 extension may thus be compactly folded so as to be completely received and housed within the pocket which is formed by the top flap 9 when the envelope is originally sealed.

10 The blank from which the envelope is formed is provided with tear lines 11 which extend parallel to the fold line 9^a of the top flap, and are slightly spaced therefrom. Adhesive 12 is applied to the space between

15 the tear lines 11, so that when the top flap is folded in sealing the envelope, the portions of the paper between the fold line 9^a and the tear lines 11 will be fastened together by the adhesive. The two tear lines 20 11 then come together and form a single tear line which is used for opening the envelope. The recipient tears off the upper edge of the envelope along the tear line 11 and free access can then be had to the interior of the envelope for the purpose of removing the enclosures. This can easily be done without danger of tearing or mutilating the member 4. The recipient can use 25 the envelope as a return envelope, and after his reply or any desired enclosures have 30 been placed therein the extension member 4 is carefully taken out of the pocket and unfolded, after which the gummed edge portions 13 thereof are moistened and the 35 extension affixed to the front of the envelope. The extension is of such a size as to cover up the original address and any other desired portions of the envelope, and may be conveniently made of substantially the 40 same size as the envelope so that it will cover the entire front thereof. When it is desired to utilize the return card 6 on the front of the envelope for the address of the envelope when it is used a second time, the 45 extension 4 is provided with a window 14 which is so positioned as to be disposed over the return card when the extension is sealed upon the front of the envelope. The window 14 may either be a transparent portion 50 provided in the paper or may be formed by cutting out a portion of the paper as may be desired. The edge of the extension 4 is preferably formed with a tongue 15 which folds around the lower edge of the 55 envelope and fits against the back thereof when the extension is in position on the front of the envelope, thereby giving additional security to the envelope and rendering it improbable that the extension will 60 be torn away from the envelope or mutilated during transit.

The cancelled stamp which was used when sending the envelope in the first place is covered up by the extension 4, and a suitable stamp 16 for use in carrying the en-

velope on its return journey may be applied to the extension at the proper position, as indicated on the drawings.

With the foregoing construction it will be obvious that the envelope is effectively 70 sealed on both the original journey and the return journey. The envelope can be readily sealed a second time after it has been originally opened, and when used as a return envelope there is no possibility of an 75 incorrect address being placed thereon for the reason that the original return card is used as the forwarding address when the envelope is on its return journey.

Having thus described my invention, what 80 I claim as new and desire to secure by Letters Patent is,

1. A return envelope of the character described, including front and back portions, 85 a sealing flap carried by the front portion and provided at marginal portions thereof with adhesive by means of which it can be secured to the back portion to initially seal the envelope and will cooperate with the said back portion to form a pocket which is separated from the interior of the envelope by the back portion, and an extension projecting from the upper edge of the back portion and adapted to be secured to the front portion of the envelope upon the 90 second sealing thereof, said extension being compactly folded upon itself and fitted within the pocket between the sealing flap and the back when the envelope is initially sealed so that the interior of the envelope 95 is not obstructed thereby:

2. An envelope including front and back portions, a sealing flap projecting from the front and provided at marginal portions thereof with adhesive by means of which it can be secured to the back for initially sealing the envelope, and will cooperate with the said back to form a pocket, and an extension projecting from the upper edge of the back and adapted to be secured to the envelope front and extend over the address receiving portion thereof upon the second sealing of the envelope, said extension having end portions thereof separated from the back by slits so that said end portions can be folded transversely and the extension further folded longitudinally so that it will be received within the before mentioned pocket between the sealing flap and back upon the initial sealing of the envelope.

3. A return envelope of the character described, including front and back portions, a sealing flap carried by the front portion and provided at the end and sides thereof with adhesive by means of which it can be secured to the back portion to initially seal the envelope and will cooperate with the said back portion to form a pocket which is separated from the interior of the envelope by the back portion, and an exten-

sion projecting from the upper edge of the back portion and adapted to be secured to the front portion of the envelope upon the second sealing thereof, said extension being of substantially the same size as the front portion of the envelope and being compactly folded upon itself both longitudinally and transversely of itself to fit within the pocket between the sealing flap and the back and leave the interior of the envelope unobstructed when the envelope is initially sealed.

In testimony whereof I affix my signature.

JOHN A. KAYE.
